UNITED STATES PATENT OFFICE.

MICHAEL J. RIORDAN, OF BISBEE, ARIZONA.

APPARATUS FOR PRODUCING REFRIGERATION.

1,118,809.

Specification of Letters Patent. Patented Nov. 24, 1914.

Application filed October 14, 1911. Serial No. 654,766.

To all whom it may concern:

Be it known that I, MICHAEL J. RIORDAN, a citizen of the United States of America, residing at Bisbee, in the county of Cochise 5 and State of Arizona, have invented certain new and useful Improvements in Apparatus for Producing Refrigeration, of which the following is a specification.

The present invention relates to a process 10 of and apparatus for refrigeration and has for its purpose to devise a method of extracting heat from the space which is to be refrigerated; and to accomplish the same in a more expeditious, convenient, and cheaper 15 manner than heretofore proposed.

The further purpose is to devise a process 20 of refrigeration which may be carried out in practice whether the space to be cooled be an ice chest, ordinary refrigerator, or room; and in fact may be utilized for cooling comparatively large spaces such as buildings.

With these and other objects in view the invention consists in the arrangement and combination of parts hereinafter claimed, 25 and while the invention is not restricted to the exact details shown and described, still for the purpose of disclosure reference is had to the accompanying drawings, in which like reference characters designate the same 30 parts in the several views; and in which:— a suitable apparatus for carrying the principles into effect is shown in the accompanying drawings wherein:—

Figure 1 is a front elevation of an ordinary 35 refrigerator with my improved apparatus installed. Fig. 2 is a central vertical sectional view thereof. Fig. 3 is a vertical sectional view taken at right angles to Fig. 3. Fig. 4 is a transverse sectional view of Fig. 2 40 taken on the line 4—4; and Fig. 5 is a detail view in front elevation disclosing one of the water evaporating devices.

Referring to the construction in detail and 45 wherein like characters of reference indicate corresponding parts in the different views shown 1 designates the refrigerator outer walls and 2 the inner walls thereof which are spaced from said outer walls 1 to receive suitable packing 3 of non-heat 50 conducting material. The bottom 4 of the refrigerator is in like manner spaced from the bottom 5 of the inner walls and the space between the bottoms 4 and 5 is also filled with packing 6.

Mounted within the chamber provided by

the inner walls 2 is a metallic casing consisting of an upper section 7, a lower section 8, and an intermediate section 9; said sections being suitably connected as by the corner angle bars 10. Said sections are of such dimensions as will provide a front space or chamber 11 and a similar and rear chamber 12. Both of the chambers 11 and 12 extend for substantially the full height of the refrigerator, and the bars 10 provide transverse chambers or passage ways 13 and 14 which afford direct communication between said chambers 11 and 12 for the purpose which will be presently set forth.

The upper section 7 contains a casing or receptacle 15 which is suitably spaced from the walls of said section to receive a packing 16, the purpose of which will be obvious. The receptacle 15 has mounted therein a plurality, preferably three, trays or pans 17, 18 75 and 19 adapted to contain the water or other liquid which is to be evaporated. Two series of pipes 20 are disposed in parallel relation and immediately over the trays 18 and 19 and are secured in position through 80 the medium of the inner and outer walls of the upper section 7, as shown in Fig. 2. In like manner a series of parallel pipes 21 is located over the upper tray 17, and said pipes 21 are similarly secured within the 85 casing 7. The series of pipes 20 bring the front and rear chambers 11 and 12 respectively into direct communication while the series of pipes 21 are provided with upwardly extending portions 22 that communicate with the atmosphere, and at their rear ends said pipes 21 communicate with the passage way or flue 23 as clearly shown in Fig. 2. The flue 23 extends to a point below the intermediate section 9, and communicates with the lower section 8, and into which it delivers currents of cool air which was taken in at the inlets 22 as will be presently explained.

The lower section 8 is provided with trays 100 or shelves 24 on which may be supported the food-stuffs to be preserved, and access is had to said shelves through a door 25 having hinges 26 that are secured to the refrigerator outer wall. A pipe 27 serves to communicate the lower section 8 with the atmosphere to carry off the air brought in by the pipe 23.

The intermediate section 9 is provided with a corrugated bottom or tray 28, that 110

is designed to support a block of ice in the event that ice is to be used. A drip pipe 29 extends from the chamber of the receptacle 9 to a point below the refrigerator as shown in Fig. 2. A water cooler 30 is secured within the chamber of the section 9 and has a faucet 31. Access is had to the chamber of the section 9 through the medium of the door 32 that is mounted on hinges 33 secured to the refrigerator outer wall.

10 The spaces 11 and 12 are designed to receive brine which constitutes the refrigerant and said refrigerant has its temperature constantly kept to a low degree through the principle of water evaporation to which end the several water trays in the upper section are provided. Evaporation of the water in these trays is effected through the medium of fabric sections 34 that are hung over the 15 pipes 20 and 21 in close arrangement. Each of said pipes is further provided with the fibrous covering 35. The fabric sections 34 are secured to wire fabrics 36, which overlie the fabrics 35 in preferably that manner shown in Fig. 5. The ends of the fabrics 34 are so adjusted as to be submerged in the water or other liquid contained in the trays, and through capillary attraction the water in these trays is being constantly absorbed 20 by the fabrics 34 and from said fabrics the water is evaporated as will be understood. To facilitate this evaporation the refrigerator outer walls 1 are cut away as at 37 in Fig. 1 which, as will be understood, exposes 25 all of the series of fabrics to the external atmosphere.

In operation the brine through having its temperature lowered by the cooling pipes 20, due to the water evaporation as just explained, tends to flow downwardly or around that portion of the refrigerator which is designed to be cooled and as the temperature rises said brine will tend to travel upwardly whence it can pass through 30 a series of pipes 20 and has its temperature again lowered. In like manner the currents of air passing through the pipes 21 is caused to pass downwardly through the passageway 23 and into the chamber of the lower section 8 from which chamber said air passes off through the pipe 27 as its temperature rises.

The chambers 11 and 12 are each open at the top as indicated by the characters 38 and 39 for the purpose of pouring in the brine. 35 Outlet pipes 40 and 41 communicate with the bottoms of the chambers 11 and 12 for drawing off the brine.

It is obvious that those skilled in the art 40 may vary the details of construction and arrangement of parts without departing from the spirit of my invention, and therefore I do not wish to be limited to such features except as may be required by the 45 claims.

What I claim as new and desire to protect by United States Letters Patent is:—

1. In a refrigerating apparatus, the combination of vessels adapted to hold brine; pans between said vessels adapted to hold water for evaporation; a closed conduit connecting said vessels and passing over one of said pans, adapted to permit a flow of brine therethrough; a plurality of pipes passing immediately over one of said pans and adapted to conduct currents of air thereover; and means for spreading water from said pans over said conduit and said pipes.

2. In a refrigerating apparatus, the combination of brine vessels; a pan between said brine vessels adapted to hold water for evaporation; a plurality of pipes passing immediately over said pan, adapted to permit the flowing of brine therethrough, and connecting said brine vessels; and means for spreading water from said pans over said pipes.

3. In a refrigerating apparatus, the combination of brine vessels; a lower water pan between said brine vessels, adapted to hold water for evaporation; brine conduits passing over said pan, adapted to permit of flowing of brine therethrough and connecting said brine vessels; an absorbent element on said brine conduits, adapted to take up the water from said water pan by capillary action; an upper water pan; and air conduits passing immediately over said upper water pan, adapted to conduct currents of air over said upper water pan.

4. In a refrigerating apparatus, the combination of brine vessels; a lower water tray between said brine vessels, adapted to hold water for evaporation; a plurality of brine conduits passing immediately over said lower water tray, connecting said brine vessels and adapted to permit of flowing brine therethrough; a refrigerating chamber; a plurality of air conduits passing immediately over said upper water tray and adapted to conduct currents of air over said upper water tray; means for conducting said air currents to and from said refrigerating chamber; and absorbent elements on said conduits adapted to take up water for evaporation from said trays by capillary attraction.

5. In a refrigerating apparatus, the combination of brine vessels, adapted to hold brine and providing an upper and a lower chamber; said lower chamber providing a provision receptacle; insulation for said brine vessels; an independent insulation for said upper chamber; a plurality of water pans mounted in said upper chamber and adapted to hold water for evaporation; brine conduits passing immediately over one of said water pans, and connecting said brine vessels and adapted to permit of flowing brine therethrough; air conduits passing immediately over the other of said water pans and

- adapted to conduct currents of air over said pan; means for conducting said air currents to and from said lower chamber; and absorbent elements overlying said conduits 5 over said pans, adapted to take up water from said pans by capillary action for evaporation.
6. In refrigerating apparatus, brine chambers; an evaporation chamber between said 10 brine chambers, for cooling the brine in said brine chambers by evaporation; a refrigerating chamber; water trays in said evaporation chamber; brine conduits passing across said evaporation chamber and connecting said brine chambers; air conduits 15
- passing through said evaporation chamber, the upper end of which communicates with the atmosphere and the lower end with said refrigerating chamber; a conduit connecting said refrigerating chamber with the 20 atmosphere; an absorbent water-distributing elements for distributing water for evaporation over said conduits.

In testimony whereof I affix my signature in presence of two witnesses.

MICHAEL J. RIORDAN.
